UNITED STATES PATENT OFFICE.

RAIMUND SCHUSTER, OF MARKNEUKIRCHEN, GERMANY.

STRING-ADJUSTER FOR GUITARS.

SPECIFICATION forming part of Letters Patent No. 577,627, dated February 23, 1897.

Application filed October 31, 1896. Serial No. 610,719. (No model.)

To all whom it may concern:

Be it known that I, RAIMUND SCHUSTER, a subject of the Emperor of Germany, residing at Markneukirchen, in the Kingdom of Saxony, Germany, have invented certain new and useful Improvements in String-Adjusters called "Accord-Revolvers" for Guitars and Similar String Instruments to Adjust the Length of the Strings for Different Accords; and I do hereby declare the following to be a full, clear, and exact description of the invention, such as will enable others skilled in the art to which it appertains to make and use the same.

15 The object of the present invention is an instrument which can easily be applied to a guitar or a similar string instrument, so as to shorten the strings more or less in order to have the instrument tuned in another key.

20 This string-adjuster greatly facilitates the playing of the guitar, and its application is a very important innovation in learning to play, for it is only necessary to practice the three easiest touches, producing the E A D 25 accords, and the player is immediately ready to play all other accords on the guitar. These touches are played without the use of the thumb of the left hand.

The adjuster is so arranged that during the 30 playing it can be displaced immediately on the guitar, pressing down all the strings on the instrument simultaneously and quickly, so that the touches of the fingers produce the accords in another key.

35 The improved string-adjuster is shown in the accompanying drawing in a perspective view, the different parts being marked by letters, to which reference will be had in the following description.

40 A U-shaped metal frame *k* is provided with two lateral jaws *h*, from which two standards *a* project upwardly, being adapted to receive in suitable bearings a roller *c*, made of metal, wood, or other suitable material, and being 45 covered with a soft substance, such as felt, leather, cloth, &c.

From the lower part of the frame *k* a spoon-shaped lever *b* projects forward, and to the left-hand-side jaw *h* a ring *d* is secured by a 50 riveted screw, which is cut open and is of steel or other metal of a resilient nature, so

as to allow the thumb to be placed in and to be securely held. The bearings carrying the cylinder *c* may be of any convenient construction. One standard is simply provided 55 with a point entering a center mark in one end of the cylinder *c*, while a similar center mark at the other end is supported by the point of a screw *e*, which is screwed into the upper end of the standard *a*. 60

In order to use this adjuster on a guitar, the screw *e* is unscrewed and the cylinder *c* is taken out. Then the U-shaped frame is placed around the neck of the guitar, so that the lever *b* points toward the body of the instrument. Thereupon the cylinder is brought back in its position by tightening the small screw *e*, so that the center marks *f* and *g* are supported in the respective pins of the place. The cylinder *c* will then touch all the strings 70 on the keyboard. The player inserts now the thumb of his left hand into the ring *d* and allows the lever *b* to rest in the palm of his hand. This enables him to displace the string-adjuster easily along the keyboard, and by giving a pressure with his hand on the lever *b* the cylinder *c* is pressed down on the strings at any desired position or upon any of the frets, so that the instrument is instantly tuned 75 according to another key. It is thus sufficient 80 to use only three fingers of the left hand to play all accords on the guitar and to play them all without the use of the thumb of the left hand. The change of keys is extremely easy, as the adjuster can be displaced in 85 instantly during the play. All the difficult touches necessary heretofore are no more necessary and everybody will be able to learn to play the guitar in a short time and without employing a teacher. 90

The three easiest touches on the guitar are the E A D accords, which are executed in the following manner: E accord: The E bass string is left open, one finger is pressed down on the first fret of the G string, producing G 95 sharp, and the B and E strings are left open. A accord: Leave A string empty, place one finger on the G string, second fret, producing A, and another finger on the B string on second fret, producing C sharp, the E string remaining empty. D accord: Leave D string empty, place one finger on the second fret of the G 100

string, producing A, place the second finger on the third fret of the B string, producing D, and the third finger on the second fret of the E string, producing F sharp.

- 5 In using the hand, as above indicated, for the E accord and in shifting the adjuster it becomes possible to sound all the accords having their keynote on the E bass string, and in placing the fingers, as above indicated, for 10 the A accord all accords can be played, by shifting the adjuster, having their keynote on the A string, and by using the position of the fingers, as indicated by the D accord, all accords with their keynote on the D string can 15 be sounded by placing the cylinder *c* always upon the fret of the note, which indicates the keynote of the accord to be played when by pressure the strings are shortened.

Having thus described my invention, what

I claim as new, and desire to secure by Letters 20 Patent, is—

A string-adjuster for guitars and similar string instruments composed of a frame adapted to partially surround the neck of the instrument and carrying in bearings a roller, 25 rolling upon the strings and being provided with a lever *B*, serving to operate the adjuster and provided with a ring adapted to receive the thumb of the player for shifting the adjuster along the keyboard, substantially as described.

In testimony whereof I affix my signature in presence of two witnesses.

RAIMUND SCHIUSTER.
